UNITED STATES PATENT OFFICE.

CASSIUS M. MCCLUNE, OF GALETON, PENNSYLVANIA.

CAR-COUPING.

SPECIFICATION forming part of Letters Patent No. 731,318, dated June 16, 1903.

Application filed March 4, 1903. Serial No. 146,136. (No model.)

To all whom it may concern:

Be it known that I, CASSIUS M. MCCLUNE, a citizen of the United States, residing at Galeton, in the county of Potter and State of Pennsylvania, have invented new and useful Improvements in Car-Couplers, of which the following is a specification.

This invention relates to new and useful improvements in car-couplers; and its object is to provide a coupler of the "Janney" type having a knuckle-operating lever in the head thereof and a sliding weighted pin so arranged as to operate said lever when desired.

Another object is to provide means for promptly returning said lever and pin to normal position when said pin is released.

A further object is to so locate the pin as to enable the same to be used in locking the knuckle in closed position.

With the above and other objects in view the invention consists in the further novel construction, combination, and arrangement of the several parts, which will be more fully hereinafter described and claimed, and illustrated in the accompanying drawings, in which—

Figure 1 is a vertical section through a coupler constructed in accordance with my invention, and Fig. 2 is a horizontal section thereof.

Referring to the figures by numerals of reference, 1 is a draw-head having ears 2 extending therefrom, within which is pivoted a knuckle 3. An arm 4 projects into the draw-head from the knuckle, and a lever 5 is fulcrumed within said draw-head and extends in rear of arm 4. A pin 6 extends transversely of the draw-head, near the top thereof, and projects through a slot 7, formed longitudinally within the upper portion of a weighted pin 8. This pin is suspended in front of the inner curved end of lever 5, and a rod 9 or other device extends therefrom through an aperture 10, formed in the top of the draw-head. The normal position of pin 8 is in the path of the end of arm 4, as illustrated in Fig. 2, and said arm cannot be swung forward unless the pin 8 is drawn back by means of the rod 9. The lower end of pin 8 is beveled, as shown at 11, and a spring-plate 12 is arranged within the draw-head and below said end and terminates in an upwardly-

curved spring 13, which projects in the rear of the inner end of lever 5.

As above stated, the arm 4 and knuckle 3, connected therewith, are normally locked in closed position, because the pin 8 normally hangs at a point in the path of the inner end of arm 4. When it is desired to uncouple, the arm 9 is drawn upward, thereby causing pin 8 to swing upon the pin 6 and at the same time slide thereon. When the pin comes into contact with the inner end of lever 5, said lever is swung upon its fulcrum and tensions the spring 13 and at the same time throws arm 4 outward. When the rod 9 is released, the pin drops into normal position and spring 13 throws lever 5 back into its original position. This movement of the spring also serves to assist the pin in traveling downward upon the inclined plate 12 into position. When two draw-heads similar to the one above described are brought together and the knuckles forced inward, the arms 4 thereof upon coming into contact with the pins 8 will force them backward, and thereby tension the spring 13. As soon as the pins are passed they will be forced to their original positions by the springs 13, and the arms 4 and knuckles 3 will then be secured. If desired, the spring 13 may be dispensed with and gravity alone resorted to for returning the locking-pin to normal position.

In the foregoing description I have shown the preferred form of my invention; but I do not limit myself thereto, as I am aware that modifications may be made therein without departing from the spirit or sacrificing the advantages thereof, and I therefore reserve the right to make such changes as fairly fall within the scope of my invention.

Having thus described the invention, what is claimed as new is—

1. In a coupler, the combination with a draw-head having a knuckle pivoted thereto, and an inwardly-extending arm to the knuckle; of a lever fulcrumed within the draw-head and extending in rear of said arm, a slotted locking-pin within the draw-head and normally in the path of the arm, a beveled end to the pin, and an inclined plate for guiding said pin to normal position.

2. In a coupler, the combination with a draw-head having a knuckle pivoted there-

to, and an arm extending inward from the knuckle; of a lever fulcrumed in the draw-head and extending in rear of the arm, a weighted locking-pin within the draw-head 5 and in front of said lever, a beveled end to the pin, and an inclined plate for guiding said pin into the path of the arm.

3. In a coupler, the combination with a draw-head having a knuckle pivoted thereto, 10 and an arm extending inward from the knuckle; of a lever fulcrumed within and extending in rear of the arm, a slotted locking-pin mounted within the draw-head and in front of the lever, means for sliding and 15 swinging said pin within the draw-head, and an inclined plate for guiding the pin into the path of the arm.

4. In a coupler, the combination with a

draw-head having a knuckle pivoted thereto, 20 and an arm extending into the head from the coupler; of an inclined plate within the draw-head, a spring extending therefrom, a lever fulcrumed within the draw-head and in rear of the arm, said spring bearing upon the lever, a transversely-extending pin within the 25 draw-head, a slotted locking-pin suspended therefrom and normally in the path of the arms, and means for removing said pin from the arm.

In testimony whereof I affix my signature 30 in presence of two witnesses.

CASSIUS M. MCCLUNE.
